UNITED STATES PATENT OFFICE.

MERRILL H. BALDWIN, OF SAN DIEGO, CALIFORNIA.

SANITARY TOILET ATTACHMENT.

1,149,109.

Specification of Letters Patent.

Patented Aug. 3, 1915.

Application filed August 22, 1914. Serial No. 858,140.

To all whom it may concern:

Be it known that I, MERRILL H. BALDWIN, a citizen of the United States of America, residing at San Diego, in the county of San Diego and State of California, have invented certain new and useful Improvements in Sanitary Toilet Attachments, of which the following is a specification.

This invention relates to sanitary attachments for closet seats and it has for its object the provision of an improved device of this nature so constructed as to automatically move into protective position over the closed seat a sheet of paper perforated in such manner as to prevent the person of the user from coming into actual contact with the closet seat and also arranged to spray the used portions of the paper with an antiseptic solution.

Further objects and advantages of the invention will be set forth in the detailed description which now follows:

In the accompanying drawing: Figure 1 is a front elevation of a closet seat provided with the attachment. Fig. 2 is a plan view thereof. Fig. 3 is a sectional view through the case 2 at the left of Fig. 2 and Fig. 4 is a sectional view of a part of the closet seat illustrating a flap breaker hereinafter described.

Like numerals designate corresponding parts in all of the figures of the drawing.

Referring to the drawing the numeral 5 designates the closet bowl, 6 the seat and 7 the lid all of the usual construction. At each side of the bowl the seat carries a casing one of which is designated 8 and constitutes a casing for a supply roll of paper 9 the web 10 of paper being carried therefrom across the top of the seat and being wound upon the used paper roll 11 in casing 12.

To impart movement to roll 11 for the purpose of winding the paper thereon I mount upon the shaft 13 of said roll a friction disk 14 which is in turn engaged by a friction disk 15 mounted upon a shaft 16. This shaft 16 has motion imparted thereto by means of sprocket wheel 17, sprocket chain 18 and sprocket wheel 19, the latter being provided with an internal ratchet 20 which is in turn engaged by a pawl 21 carried by a disk 22 fast upon a rod 23 to which the lid 7 is secured. Therefore when the lid is raised no motion is imparted to the paper web but when the lid is lowered roll

11 will be turned, through the connections described to wind the web 10 of paper thereon. By referring to Fig. 2 it will be seen that the paper web is cut out or perforated at intervals as at 24 the resulting openings being slightly smaller than the opening in the closet seat whereby the person of the user is prevented from coming into contact with the closet seat.

For spraying that portion of the paper web that has been wound upon the roll 11 with an antiseptic solution a pump 25 is mounted in casing 12 and is supplied with such solution from a supply tank 26 through suction pipe 27. A discharge pipe 28 leads from the pump and is perforated to cause it to spray the antiseptic solution upon the used paper. For imparting movement to the pump plunger the pump rod 29 is provided with a rack 29^a which meshes with a gear wheel 29^b fast upon rod 23. Consequently as the lid 7 is raised and lowered reciprocation is imparted to the pump rod for actuating the pump plunger. In order to insure the lid always being lowered so that the lid cannot be raised and left raised, I preferably provide a spring 30 arranged to throw the lid to its lowered position.

It is desired to provide means for actuating the flush cord simultaneously with the lowering of the lid, and to that end there is a slidably mounted bar 31 beneath the pump rod 29, having hingedly connected to its front end at 32, a tongue 33 which is provided with a notch 34 adapted to be engaged by tooth 35 carried by the pump rod. A spring 36 secured to the bar 31 normally tends to throw the tongue 33 upwardly. As the lid is lowered and the pump rod moves toward the left the tooth 35 moves bar 31 and tongue 33 likewise toward the left, the beveled end 33^a of said tongue at this time being forced downward by a pin 37 until the notch 34 is freed from tooth 35. But by this time, a pull has been imparted to the flush cord 38 and the cord is thereupon released and the bar 31 is permitted to move again to the right, but upon the movement of the pump rod toward the right, tooth 35 again engages in notch 34 preparatory to repeating this operation. Pump rod 29 preferably carries a handle 39 which travels in the slot 40 which slot is provided with a lateral recess 41 in which said handle may be engaged to thereby hold the lid in its elevated position. Whenever said handle is

released from the notch the spring 30 acts to force the lid downwardly to carry out the foregoing operations.

As is best illustrated in Fig. 2 the openings in the paper web are not of complete oval formation, but comprise flap portions 42 which are united at 43, 44, and 45 and means are provided for breaking these flap portions loose at the points 44 and 45 and 10 permitting these flap portions to be forced downwardly at the front of the bowl.

I preferably provide upon the lid (see Fig. 4) a flap breaker comprising a centrally arranged bar 46 which is mounted upon a transverse shaft 47 and which is under the influence of the spring 48 which normally tends to throw it to the dotted line position shown in Fig. 4. Upon the outer end of the shaft 47 is a crank arm 49 to which is connected a cable 50 which passes over a roller 51 and is attached at 52 to that part of the seat which lies to one side of the central opening in said seat. When the lid is raised, the pull upon the cable 50 pulls downwardly 15 upon crank arm 49 and moves the breaker 46 back into the recess 52^a; but when the lid is lowered this cable is slackened and the spring 48 may act to force the breaker into such position as to break the flap 40 loose 20 and force it downwardly in a manner that will be well understood. The reason for providing this structure is that it is desirable when the lid is raised, to have this breaker lie in such position that it will not 25 contact with the back of the person using the apparatus. This is accomplished by moving the breaker 46 back into recess 52^a, and since the crank arm 49 lies considerably to one side of the structure, this element will 30 not interfere with the user.

While the elements shown and described are well adapted to serve the purposes for which they are intended, it is to be understood that the invention is not limited to 35 the precise construction set forth, but includes within its purview such changes as may be made within the scope of the appended claims.

Having described my invention what I 40 claim is:

1. In a device of the character described the combination with a seat and lid, of a pair of rolls, adapted to have a paper web wound thereupon, and to be drawn from

one of said rolls to the other across said 55 seat, and connections between one of said rolls and said lid whereby movement of the lid imparts rotation to said roll to wind the paper web thereon, and means also actuated by said lid for spraying the used portion 60 of the paper with an antiseptic solution.

2. In a device of the character described the combination with a seat and spring actuated lid, a roll upon each side of said seat, said rolls being adapted to have a 65 paper web wound from one to the other thereof, a rod upon which said lid is fixed, a pawl carried by said rod, a ratchet with which said pawl engages, said ratchet being formed upon a rotative member, a shaft, 70 means for driving said shaft from said rotative member, a friction disk mounted upon said shaft and a friction disk mounted upon one of said rolls, the periphery of the first named friction disk bearing upon the face 75 of the last named friction disk, a pump, a supply tank for said pump, a spray pipe leading from said pump and arranged in juxtaposition to the used paper roll, and means for actuating said pump from said 80 lid.

3. In a device of the character described the combination with a seat and spring actuated lid, a roll upon each side of said seat, said rolls being adapted to have a paper web 85 wound from one to the other thereof, a rod upon which said lid is fixed, a pawl carried by said rod, a ratchet with which said pawl engages, said ratchet being formed upon a rotative member, a shaft, means for driving 90 said shaft from said rotative member, a friction disk mounted upon said shaft and a friction disk mounted upon one of said rolls, the periphery of the first named friction disk bearing upon the face of the last named 95 friction disk, a pump, a supply tank for said pump, a spray pipe leading from said pump and arranged in juxtaposition to the used paper roll, the means for actuating said pump from said lid, said last named means 100 comprising a rack carried by the pump rod and a gear wheel movable with the lid.

In testimony whereof I affix my signature in presence of two witnesses.

MERRILL H. BALDWIN.
